UNITED STATES PATENT OFFICE

167,150

COMBINED BASE AND UPRIGHT FOR A FOOD MIXER OR THE LIKE

Ivar Jepson, Oak Park, Ill., assignor to Sunbeam Corporation, Chicago, Ill., a corporation of Illinois

Application January 16, 1951, Serial No. 13,826

Term of patent 14 years

(Cl. D44—7)

To all whom it may concern:

Be it known that I, Ivar Jepson, a citizen of the United States, residing at Oak Park, in the county of Cook and State of Illinois, have invented a new, original, and ornamental Design for a Combined Base and Upright for a Food Mixer or the like, of which the following is a specification, reference being had to the accompanying drawings, forming part thereof.

In the drawings:

Figure 1 is a side elevational view of a combined base and upright for a food mixer or the like, embodying my new design;

Fig. 2 is a sectional view taken substantially along the line 2—2 of Figure 1; and

Figs. 3 and 4 are front and rear elevational views, respectively.

I claim:

The ornamental design for a combined base and upright for a food mixer or the like, substantially as shown.

IVAR JEPSON.
